UNITED STATES PATENT OFFICE.

FRANK F. FISCHER, OF OKLAHOMA CITY, OKLAHOMA.

DESIGN FOR A MEMORIAL GRAVE MARKER.

Application filed February 16, 1928. Serial No. 25,453. Term of patent 3½ years.

To all whom it may concern:

Be it known that I, FRANK F. FISCHER, a citizen of the United States, residing at Oklahoma City, in the county of Oklahoma and State of Oklahoma, have invented a new, original, and ornamental Design for Memorial Grave Markers, of which the following is a specification, reference being had to the accompanying drawing, forming part thereof.

Figure 1 of the drawing is a front elevational view of the memorial grave marker showing my new design;

Fig. 2 is a side edge view thereof.

I claim:

The ornamental design for a memorial grave marker, as shown.

FRANK F. FISCHER.
